UNITED STATES PATENT OFFICE.

JOHN F. MCKELLAR, OF ST. PAUL, MINNESOTA.

GLARE SHIELD.

Application filed November 4, 1926. Serial No. 146,230.

This invention relates to improvements in glare shields for use on automobiles.

Objects of the invention are to provide a shield which can be easily and quickly adjusted to different positions, and which can be secured in such positions without the use of set screws; to provide a device in which slight translative movement of certain swingingly adjustable portions of the device in one direction acts to condition such portions for swinging, and in which translation of those portions in an opposite direction acts to positively lock the portions in adjusted position; and to provide for adjustment of the transparent element upon the adjustable portions.

Features of the invention include all details of construction, as well as combinations and subcombinations of the elements of the device.

Figure 1 is a vertical sectional view through a vehicle body showing the device applied at the inside thereof;

Figure 2 is an elevation of the device with the shield in lowermost position. In this figure the shield may be considered as placed at the outer side of the body;

Figure 3 is a detail vertical section on the line 3-3 of Figure 2 showing the device at one limit position;

Figure 4 is a view similar to Figure 3 showing the device in an intermediate position;

Figure 5 is a section on the line 5-5 of Figure 3;

Figure 6 is a sectional elevation on the line 6-6 of Figure 4.

Numeral 1 designates the vehicle body having the device mounted at the front portion and, in this instance, interiorly thereof. The device may be mounted in any desired position, and Figure 1 only illustrates one application.

The device essentially comprises a pair of spaced circular base or bracket members 3, 4, each of the members being substantially identical in structure. Each bracket member provides an upstanding flange 5, a portion 6 of which is circumferentially notched or cut. Within this cut portion, and extending towards the base side of the member, are notches 7, 8, angularly related, in this instance right-angularly. A central pivot 9 in the form of a bolt traverses an arm 10, the said arm having a slot 11 longitudinally arranged therein. This construction disposes the arm for pivotal and translative

motion. The arm has a stop 12 thereon, in this instance wedge-shaped and outwardly convergent, and adapted to engage the notched portion 7 of the base to lock the arm both against outward translation and rotation. The arm is guided by an element 14 pivoting about the bolt 9, and having flanges engaging the side or edge faces of the arm 10. In this instance, the guide has an upstanding arm or flange 15, and engaged with the flange and with the stop 12, by opposite ends, is a spring element 16 which tends to force the arm outwardly, and provides means whereby the arm may be translated inwardly against a yielding tension. The arm thus has a stop engageable with the bracket base to limit outward translation of the arm, and also to hold the same against pivotal movement. A cover 20 closes the open end of the hollow bracket or base member and forms with the cutout portion 6 a circumferential slot. The plate is suitably secured by bolts 21. In this instance, only two notches have been shown but it will be understood that any number may be employed. Each arm 10 is provided with a flange 22 at the outer portion, in this instance right angularly related, and a transparent element 25 is secured at opposite sides to respective flanges as shown in Figure 2. Each flange has a plurality of openings 26, 27, in this instance arranged in sets of three, the sets being spaced as shown. The transparent member is held by a frame 28 and this frame is suitably bored, and a bolt 29 passes through openings in frame and arm to secure plate and arms for unison movement.

By means of this device, the frame and transparent member are secured, and may be adjusted lengthwise of the arms.

When it is desired to change the angular relation of the arm with respect to the bracket base, the arm is translated inwardly to disengage the stop 12, after which the arm is swung to the desired position, according to the location of the slots, and is released, to be translated outwardly and engaged with the stop, for example as shown in dotted lines in Figure 4. By means of the spring the outer end of the stop 12 may be made to frictionally engage the inner surface of the flange, to hold the arm in an intermediate position, as shown in Figure 4. Thus for some purposes the slots or sockets 7 and 8 may be dispensed with, or some suitable equivalent means can be used.

I claim as my invention:

1. A base member having a radial notch, a pivot centrally of the base member, an arm translatable and rotatable upon the pivot, and having a stop engageable with the notch to limit pivotal and translative movement of the arm, a member engaging the arm as a guide and rotatable upon the pivot, and a spring connected to translatively urge the arm to limit position to engage its stop with the notch. 65
2. A base member having a peripheral flange and having radial notches, a pivot centrally of the base member, an arm translatable upon the pivot and arranged to ride upon the flange, said arm having a stop engageable with the notches as the arm is translated outwardly, a member engaging the arm as a guide and radially arranged with respect to the base, said guide rotatable upon the pivot, and a spring connecting guide and arm and acting to urge the arm outwardly. 70
3. A base member, a pivot centrally of the base member, an arm translatable and rotatable upon the pivot, and having a stop to frictionally engage with the base member to limit pivotal and translative movement of the arm, a member engaging the arm as a guide and rotatable upon the pivot, and a spring connected to translatively urge the arm to base-engaging position. 75
4. A base member having a peripheral flange, a pivot centrally of the base member, an arm translatable upon the pivot and arranged to ride upon the flange, said arm having a stop engageable with the flange as the arm is translated outwardly, a member engaging the arm as a guide and radially arranged with respect to the base, said guide rotatable upon the pivot, and a spring connecting guide and arm and acting to urge the arm radially across the flange. 80
5. A pair of spaced bracket members, an arm for each member connected for pivotal and translative motion, a transparent member secured transversely between the arms, each arm and corresponding bracket member being cooperable to limit pivotal and translative motion of the arm, a pivoted member engaging the arm as a guide, and a spring arranged to translatively urge the arm to a position to limit pivotal and translative motion. 85
6. A device of the class described comprising a pair of bracket members, each having angularly related notches, an arm for each base member connected for pivotal and translative motion, each arm having a stop engageable with its bracket to limit such pivotal and translative motion, pivoted members engaging each arm as guides, a spring arranged to translatively urge the arm outwardly, and a transparent plate connecting the arms transversely. 90
7. A pair of spaced bracket members, an arm for each member connected for pivotal and translative motion, a transparent member secured transversely between the arms, and adjustable lengthwise thereof, each arm and corresponding bracket member being cooperable to limit pivotal and translative motion of the arm, a pivoted member engaging the arm as a guide, and a spring arranged to translatively urge the arm to a position to limit pivotal and translative motion. 95
8. A base member, an arm connected with said base for pivotal and translative motion, said arm and base being cooperable to limit pivotal and translative motion of the arm, a pivoted member engaging the arm as a guide, and a spring arranged to translatively urge the arm to a position to limit pivotal and translative motion thereof. 100
9. A device of the class described comprising a base member, an arm connected with said base member for pivotal and translative motions in the same plane, said arm having a stop engageable with the base to limit such pivotal and translative motion, and a spring arranged to translatively urge the arm. 105
10. A base member, an arm pivotally and translatable mounted upon the base and having a stop engageable with the base to limit translation of the member in one direction and also hold the same against pivotal movement, a member pivoted to the base and guidingly engaging the arm, and a spring arranged to urge the arm outwardly. 110
11. A base member, an arm connected with said base for pivotal and translative motion in the same plane, said arm and base being cooperable to limit pivotal and translative motion of the arm, a pivoted member engaging the arm as a guide, and a spring arranged to translatively urge the arm to a position to limit pivotal and translative motion thereof. 115
12. A device of the class described comprising a base member, a guide, a pivot securing the guide to the base, an arm slideable in the guide, said arm having a slot loosely traversed by the pin, said slot elongated in direction of movement of the arm, a spring engaging guide and arm to translate the arm and means for limiting translative and pivotal movement of the arm when urged to a limit position. 120

In witness whereof, I have hereunto set my hand this 27th day of October, 1926.

JOHN F. MCKELLAR.
